UNITED STATES PATENT OFFICE

HARRY A. INMAN, OF NEWARK, NEW YORK

DUSTING DEVICE

Application filed September 25, 1925. Serial No. 58,679.

This invention relates to devices for applying a film of dust or powder to work such as sheets or webs of paper or other material or objects which have been freshly printed or otherwise coated with a substance likely to adhere to or be smeared by contact with other sheets or objects before drying, the chief object of the invention being to provide a simple and practical device of this character 5
adapted to operate in an efficient and reliable manner with a minimum of wastage of the dusting material and of attention from the operator.

To these and other ends the invention relates in certain improvements and combinations of parts, all as will be hereinafter more fully described, the novel features being pointed out in the claims at the end of the specification.

20 In the drawings:—

Figure 1 is a side elevation of an apparatus embodying the present invention, and

Figure 2 is an enlarged view of a portion of the same partly in section.

25 Similar reference numerals throughout the several views indicate the same parts.

The invention is shown in the present instance, by way of illustration, as applied to the dusting of sheets of material while carried by a conveyor, the latter being suitable as a part of or an attachment for a printing press, for example, but it will be understood that the invention is applicable as well to a variety of other mechanisms and uses.

30 In the present embodiment, there is shown a conveying mechanism comprising a frame having a pair of legs 5 at one end and at the other a pair of standards 6 serving as legs and also as upwardly extending supports for the dusting device proper. These legs or standards are interconnected by suitable cross members or braces as indicated at 7. Journaled between the upper ends of each pair of supports 5 and 6, respectively, are pulleys 8 and 9 carrying a conveyor belt 10, as shown, for sheets of paper, cardboard or the like 11. Pulley 9 carries on its shaft 9^a one or more pulleys 12 rotated by a belt connection 13 with a motor 14 on the frame and serving to drive the conveyor belt and also a belt 15

for driving the dusting device located on standards 6 above the conveyor as hereafter described. The conveyor as stated above may be a part of a printing or other work producing mechanism or may be attached to the latter for receiving sheets at its right hand end and moving the same toward the left past the dusting device as shown.

55 Standards 6 are extended upwardly above the conveyor and carry the container 16 for the dusting material or powder. Container 16 may have various forms comprising in the present instance a rear wall 17, V-shaped end walls 18 and a wall 19 preferably inclined inwardly and downwardly to the bottom of the container as shown and of a flexible perforate or foraminous character, such as afforded by a woven fabric material of suitable mesh through which dusting material such as starch may be sifted.

60 Applying means are provided in combination with the material container 16 for obtaining material therefrom and distributing or dusting the same over the work as the latter is carried past by the conveyor. A container such as described above has been found to function admirably with movable applying means of a character adapted to engage the dispensing wall portion 19 to gently vibrate the same and agitate the material to cause it 65 to sift through for distribution by the applying means over the work. It has been found also that such an applying means is admirably provided by a rotary brush preferably having flexible bristle portions of substantial 70 length and spaced circumferentially in groups as shown. These bristles 20 are mounted in any known or suitable manner in a holder 21 having a spindle 22 journaled at its ends in bracket arms 23 projecting horizontally from standards 6 below the container and over the conveyor as shown. Belt 15 is carried over an end of the brush or a pulley thereon to rotate the same. These parts are 75 so proportioned and arranged that bristles 20 during rotation engage fabric wall portion 19 of the container adjacent its bottom, as indicated in Figure 2, so as to gently vibrate the fabric, agitate the dusting material and cause it to gradually sift through.

80 At the 85 end of the conveyor belt 10, as shown in Figure 1, a pulley 16 is carried by a frame 17 which is journaled on a support 18. A belt 19 is carried over pulley 16 and a pulley 20 which is journaled on a support 21. A belt 22 is carried over pulley 20 and a pulley 23 which is journaled on a support 24. A belt 25 is carried over pulley 23 and a pulley 26 which is journaled on a support 27. A belt 28 is carried over pulley 26 and a pulley 29 which is journaled on a support 30. A belt 31 is carried over pulley 29 and a pulley 32 which is journaled on a support 33. A belt 34 is carried over pulley 32 and a pulley 35 which is journaled on a support 36. A belt 37 is carried over pulley 35 and a pulley 38 which is journaled on a support 39. A belt 40 is carried over pulley 38 and a pulley 41 which is journaled on a support 42. A belt 43 is carried over pulley 41 and a pulley 44 which is journaled on a support 45. A belt 46 is carried over pulley 44 and a pulley 47 which is journaled on a support 48. A belt 49 is carried over pulley 47 and a pulley 50 which is journaled on a support 51. A belt 52 is carried over pulley 50 and a pulley 53 which is journaled on a support 54. A belt 55 is carried over pulley 53 and a pulley 56 which is journaled on a support 57. A belt 58 is carried over pulley 56 and a pulley 59 which is journaled on a support 60. A belt 61 is carried over pulley 59 and a pulley 62 which is journaled on a support 63. A belt 64 is carried over pulley 62 and a pulley 65 which is journaled on a support 66. A belt 67 is carried over pulley 65 and a pulley 68 which is journaled on a support 69. A belt 70 is carried over pulley 68 and a pulley 71 which is journaled on a support 72. A belt 73 is carried over pulley 71 and a pulley 74 which is journaled on a support 75. A belt 76 is carried over pulley 74 and a pulley 77 which is journaled on a support 78. A belt 79 is carried over pulley 77 and a pulley 80 which is journaled on a support 81. A belt 82 is carried over pulley 80 and a pulley 83 which is journaled on a support 84. A belt 85 is carried over pulley 83 and a pulley 86 which is journaled on a support 87. A belt 88 is carried over pulley 86 and a pulley 89 which is journaled on a support 90. A belt 91 is carried over pulley 89 and a pulley 92 which is journaled on a support 93. A belt 94 is carried over pulley 92 and a pulley 95 which is journaled on a support 96. A belt 97 is carried over pulley 95 and a pulley 98 which is journaled on a support 99. A belt 100 is carried over pulley 98 and a pulley 101 which is journaled on a support 102. A belt 103 is carried over pulley 101 and a pulley 104 which is journaled on a support 105. A belt 106 is carried over pulley 104 and a pulley 107 which is journaled on a support 108. A belt 109 is carried over pulley 107 and a pulley 110 which is journaled on a support 111. A belt 112 is carried over pulley 110 and a pulley 113 which is journaled on a support 114. A belt 115 is carried over pulley 113 and a pulley 116 which is journaled on a support 117. A belt 118 is carried over pulley 116 and a pulley 119 which is journaled on a support 120. A belt 121 is carried over pulley 119 and a pulley 122 which is journaled on a support 123. A belt 124 is carried over pulley 122 and a pulley 125 which is journaled on a support 126. A belt 127 is carried over pulley 125 and a pulley 128 which is journaled on a support 129. A belt 130 is carried over pulley 128 and a pulley 131 which is journaled on a support 132. A belt 133 is carried over pulley 131 and a pulley 134 which is journaled on a support 135. A belt 136 is carried over pulley 134 and a pulley 137 which is journaled on a support 138. A belt 139 is carried over pulley 137 and a pulley 140 which is journaled on a support 141. A belt 142 is carried over pulley 140 and a pulley 143 which is journaled on a support 144. A belt 145 is carried over pulley 143 and a pulley 146 which is journaled on a support 147. A belt 148 is carried over pulley 146 and a pulley 149 which is journaled on a support 150. A belt 151 is carried over pulley 149 and a pulley 152 which is journaled on a support 153. A belt 154 is carried over pulley 152 and a pulley 155 which is journaled on a support 156. A belt 157 is carried over pulley 155 and a pulley 158 which is journaled on a support 159. A belt 160 is carried over pulley 158 and a pulley 161 which is journaled on a support 162. A belt 163 is carried over pulley 161 and a pulley 164 which is journaled on a support 165. A belt 166 is carried over pulley 164 and a pulley 167 which is journaled on a support 168. A belt 169 is carried over pulley 167 and a pulley 170 which is journaled on a support 171. A belt 172 is carried over pulley 170 and a pulley 173 which is journaled on a support 174. A belt 175 is carried over pulley 173 and a pulley 176 which is journaled on a support 177. A belt 178 is carried over pulley 176 and a pulley 179 which is journaled on a support 180. A belt 181 is carried over pulley 179 and a pulley 182 which is journaled on a support 183. A belt 184 is carried over pulley 182 and a pulley 185 which is journaled on a support 186. A belt 187 is carried over pulley 185 and a pulley 188 which is journaled on a support 189. A belt 191 is carried over pulley 188 and a pulley 192 which is journaled on a support 193. A belt 195 is carried over pulley 192 and a pulley 196 which is journaled on a support 197. A belt 199 is carried over pulley 196 and a pulley 200 which is journaled on a support 201. A belt 204 is carried over pulley 200 and a pulley 205 which is journaled on a support 206. A belt 208 is carried over pulley 205 and a pulley 209 which is journaled on a support 210. A belt 212 is carried over pulley 209 and a pulley 213 which is journaled on a support 214. A belt 216 is carried over pulley 213 and a pulley 217 which is journaled on a support 218. A belt 220 is carried over pulley 217 and a pulley 221 which is journaled on a support 222. A belt 224 is carried over pulley 221 and a pulley 225 which is journaled on a support 226. A belt 228 is carried over pulley 225 and a pulley 229 which is journaled on a support 230. A belt 232 is carried over pulley 229 and a pulley 233 which is journaled on a support 234. A belt 236 is carried over pulley 233 and a pulley 237 which is journaled on a support 238. A belt 240 is carried over pulley 237 and a pulley 241 which is journaled on a support 242. A belt 244 is carried over pulley 241 and a pulley 245 which is journaled on a support 246. A belt 248 is carried over pulley 245 and a pulley 249 which is journaled on a support 250. A belt 253 is carried over pulley 249 and a pulley 254 which is journaled on a support 255. A belt 257 is carried over pulley 254 and a pulley 258 which is journaled on a support 259. A belt 262 is carried over pulley 258 and a pulley 263 which is journaled on a support 264. A belt 267 is carried over pulley 263 and a pulley 268 which is journaled on a support 269. A belt 272 is carried over pulley 268 and a pulley 273 which is journaled on a support 274. A belt 277 is carried over pulley 273 and a pulley 278 which is journaled on a support 279. A belt 282 is carried over pulley 278 and a pulley 283 which is journaled on a support 284. A belt 287 is carried over pulley 283 and a pulley 288 which is journaled on a support 289. A belt 292 is carried over pulley 288 and a pulley 293 which is journaled on a support 294. A belt 297 is carried over pulley 293 and a pulley 298 which is journaled on a support 299. A belt 302 is carried over pulley 298 and a pulley 303 which is journaled on a support 304. A belt 307 is carried over pulley 303 and a pulley 308 which is journaled on a support 309. A belt 312 is carried over pulley 308 and a pulley 313 which is journaled on a support 314. A belt 317 is carried over pulley 313 and a pulley 318 which is journaled on a support 319. A belt 322 is carried over pulley 318 and a pulley 323 which is journaled on a support 324. A belt 327 is carried over pulley 323 and a pulley 328 which is journaled on a support 329. A belt 332 is carried over pulley 328 and a pulley 333 which is journaled on a support 334. A belt 337 is carried over pulley 333 and a pulley 338 which is journaled on a support 339. A belt 342 is carried over pulley 338 and a pulley 343 which is journaled on a support 344. A belt 347 is carried over pulley 343 and a pulley 348 which is journaled on a support 349. A belt 352 is carried over pulley 348 and a pulley 353 which is journaled on a support 354. A belt 357 is carried over pulley 353 and a pulley 358 which is journaled on a support 359. A belt 362 is carried over pulley 358 and a pulley 363 which is journaled on a support 364. A belt 367 is carried over pulley 363 and a pulley 368 which is journaled on a support 369. A belt 372 is carried over pulley 368 and a pulley 373 which is journaled on a support 374. A belt 377 is carried over pulley 373 and a pulley 378 which is journaled on a support 379. A belt 382 is carried over pulley 378 and a pulley 383 which is journaled on a support 384. A belt 387 is carried over pulley 383 and a pulley 388 which is journaled on a support 389. A belt 392 is carried over pulley 388 and a pulley 393 which is journaled on a support 394. A belt 397 is carried over pulley 393 and a pulley 398 which is journaled on a support 399. A belt 402 is carried over pulley 398 and a pulley 403 which is journaled on a support 404. A belt 407 is carried over pulley 403 and a pulley 408 which is journaled on a support 409. A belt 412 is carried over pulley 408 and a pulley 413 which is journaled on a support 414. A belt 417 is carried over pulley 413 and a pulley 418 which is journaled on a support 419. A belt 422 is carried over pulley 418 and a pulley 423 which is journaled on a support 424. A belt 427 is carried over pulley 423 and a pulley 428 which is journaled on a support 429. A belt 432 is carried over pulley 428 and a pulley 433 which is journaled on a support 434. A belt 437 is carried over pulley 433 and a pulley 438 which is journaled on a support 439. A belt 442 is carried over pulley 438 and a pulley 443 which is journaled on a support 444. A belt 447 is carried over pulley 443 and a pulley 448 which is journaled on a support 449. A belt 452 is carried over pulley 448 and a pulley 453 which is journaled on a support 454. A belt 457 is carried over pulley 453 and a pulley 458 which is journaled on a support 459. A belt 462 is carried over pulley 458 and a pulley 463 which is journaled on a support 464. A belt 467 is carried over pulley 463 and a pulley 468 which is journaled on a support 469. A belt 472 is carried over pulley 468 and a pulley 473 which is journaled on a support 474. A belt 477 is carried over pulley 473 and a pulley 478 which is journaled on a support 479. A belt 482 is carried over pulley 478 and a pulley 483 which is journaled on a support 484. A belt 487 is carried over pulley 483 and a pulley 488 which is journaled on a support 489. A belt 492 is carried over pulley 488 and a pulley 493 which is journaled on a support 494. A belt 497 is carried over pulley 493 and a pulley 498 which is journaled on a support 499. A belt 502 is carried over pulley 498 and a pulley 503 which is journaled on a support 504. A belt 507 is carried over pulley 503 and a pulley 508 which is journaled on a support 509. A belt 512 is carried over pulley 508 and a pulley 513 which is journaled on a support 514. A belt 517 is carried over pulley 513 and a pulley 518 which is journaled on a support 519. A belt 522 is carried over pulley 518 and a pulley 523 which is journaled on a support 524. A belt 527 is carried over pulley 523 and a pulley 528 which is journaled on a support 529. A belt 532 is carried over pulley 528 and a pulley 533 which is journaled on a support 534. A belt 537 is carried over pulley 533 and a pulley 538 which is journaled on a support 539. A belt 542 is carried over pulley 538 and a pulley 543 which is journaled on a support 544. A belt 547 is carried over pulley 543 and a pulley 548 which is journaled on a support 549. A belt 552 is carried over pulley 548 and a pulley 553 which is journaled on a support 554. A belt 557 is carried over pulley 553 and a pulley 558 which is journaled on a support 559. A belt 562 is carried over pulley 558 and a pulley 563 which is journaled on a support 564. A belt 567 is carried over pulley 563 and a pulley 568 which is journaled on a support 569. A belt 572 is carried over pulley 568 and a pulley 573 which is journaled on a support 574. A belt 577 is carried over pulley 573 and a pulley 578 which is journaled on a support 579. A belt 582 is carried over pulley 578 and a pulley 583 which is journaled on a support 584. A belt 587 is carried over pulley 583 and a pulley 588 which is journaled on a support 589. A belt 592 is carried over pulley 588 and a pulley 593 which is journaled on a support 594. A belt 597 is carried over pulley 593 and a pulley 598 which is journaled on a support 599. A belt 602 is carried over pulley 598 and a pulley 603 which is journaled on a support 604. A belt 607 is carried over pulley 603 and a pulley 608 which is journaled on a support 609. A belt 612 is carried over pulley 608 and a pulley 613 which is journaled on a support 614. A belt 617 is carried over pulley 613 and a pulley 618 which is journaled on a support 619. A belt 622 is carried over pulley 618 and a pulley 623 which is journaled on a support 624. A belt 627 is carried over pulley 623 and a pulley 628 which is journaled on a support 629. A belt 632 is carried over pulley 628 and a pulley 633 which is journaled on a support 634. A belt 637 is carried over pulley 633 and a pulley 638 which is journaled on a support 639. A belt 642 is carried over pulley 638 and a pulley 643 which is journaled on a support 644. A belt 647 is carried over pulley 643 and a pulley 648 which is journaled on a support 649. A belt 652 is carried over pulley 648 and a pulley 653 which is journaled on a support 654. A belt 657 is carried over pulley 653 and a pulley 658 which is journaled on a support 659. A belt 662 is carried over pulley 658 and a pulley 663 which is journaled on a support 664. A belt 667 is carried over pulley 663 and a pulley 668 which is journaled on a support 669. A belt 672 is carried over pulley 668 and a pulley 673 which is journaled on a support 674. A belt 677 is carried over pulley 673 and a pulley 678 which is journaled on a support 679. A belt 682 is carried over pulley 678 and a pulley 683 which is journaled on a support 684. A belt 687 is carried over pulley 683 and a pulley 688 which is journaled on a support 689. A belt 692 is carried over pulley 688 and a pulley 693 which is journaled on a support 694. A belt 697 is carried over pulley 693 and a pulley 698 which is journaled on a support 699. A belt 702 is carried over pulley 698 and a pulley 703 which is journaled on a support 704. A belt 707 is carried over pulley 703 and a pulley 708 which is journaled on a support 709. A belt 712 is carried over pulley 708 and a pulley 713 which is journaled on a support 714. A belt 717 is carried over pulley 713 and a pulley 718 which is journaled on a support 719. A belt 722 is carried over pulley 718 and a pulley 723 which is journaled on a support 724. A belt 727 is carried over pulley 723 and a pulley 728 which is journaled on a support 729. A belt 732 is carried over pulley 728 and a pulley 733 which is journaled on a support 734. A belt 737 is carried over pulley 733 and a pulley 738 which is journaled on a support 739. A belt 742 is carried over pulley 738 and a pulley 743 which is journaled on a support 744. A belt 747 is carried over pulley 743 and a pulley 748 which is journaled on a support 749. A belt 752 is carried over pulley 748 and a pulley 753 which is journaled on a support 754. A belt 757 is carried over pulley 753 and a pulley 758 which is journaled on a support 759. A belt 762 is carried over pulley 758 and a pulley 763 which is journaled on a support 764. A belt 767 is carried over pulley 763 and a pulley 768 which is journaled on a support 769. A belt 772 is carried over pulley 768 and a pulley 773 which is journaled on a support 774. A belt 777 is carried over pulley 773 and a pulley 778 which is journaled on a support 779. A belt 782 is carried over pulley 778 and a pulley 783 which is journaled on a support 784. A belt 787 is carried over pulley 783 and a pulley 788 which is journaled on a support 789. A belt 792 is carried over pulley 788 and a pulley 793 which is journaled on a support 794. A belt 797 is carried over pulley 793 and a pulley 798 which is journaled on a support 799. A belt 802 is carried over pulley 798 and a pulley 803 which is journaled on a support 804. A belt 807 is carried over pulley 803 and a pulley 808 which is journaled on a support 809. A belt 812 is carried over pulley 808 and a pulley 813 which is journaled on a support 814. A belt 817 is carried over pulley 813 and a pulley 818 which is journaled on a support 819. A belt 822 is carried over pulley 818 and a pulley 823 which is journaled on a support 824. A belt 827 is carried over pulley 823 and a pulley 828 which is journaled on a support 829. A belt 832 is carried over pulley 828 and a pulley 833 which is journaled on a support 834. A belt 837 is carried over pulley 833 and a pulley 838 which is journaled on a support 839. A belt 842 is carried over pulley 838 and a pulley 843 which is journaled on a support 844. A belt 847 is carried over pulley 843 and a pulley 848 which is journaled on a support 849. A belt 852 is carried over pulley 848 and a pulley 853 which is journaled on a support 854. A belt 857 is carried over pulley 853 and a pulley 858 which is journaled on a support 859. A belt 862 is carried over pulley 858 and a pulley 863 which is journaled on a support 864. A belt 867 is carried over pulley 863 and a pulley 868 which is journaled on a support 869. A belt 872 is carried over pulley 868 and a pulley 873 which is journaled on a support 874. A belt 877 is carried over pulley 873 and a pulley 878 which is journaled on a support 879. A belt 882 is carried over pulley 878 and a pulley 883 which is journaled on a support 884. A belt 887 is carried over pulley 883 and a pulley 888 which is journaled on a support 889. A belt 892 is carried over pulley 888 and a pulley 893 which is journaled on a support 894. A belt 897 is carried over pulley 893 and a pulley 898 which is journaled on a support 899. A belt 902 is carried over pulley 898 and a pulley 903 which is journaled on a support 904. A belt 907 is carried over pulley 903 and a pulley 908 which is journaled on a support 909. A belt 912 is carried over pulley 908 and a pulley 913 which is journaled on a support 914. A belt 917 is carried over pulley 913 and a pulley 918 which is journaled on a support 919. A belt 922 is carried over pulley 918 and a pulley 923 which is journaled on a support 924. A belt 927 is carried over pulley 923 and a pulley 928 which is journaled on a support 929. A belt 932 is carried over pulley 928 and a pulley 933 which is journaled on a support 934. A belt 937 is carried over pulley 933 and a pulley 938 which is journaled on a support 939. A belt 942 is carried over pulley 938 and a pulley 943 which is journaled on a support 944. A belt 947 is carried over pulley 943 and a pulley 948 which is journaled on a support 949. A belt 952 is carried over pulley 948 and a pulley 953 which is journaled on a support 954. A belt 957 is carried over pulley 953 and a pulley 958 which is journaled on a support 959. A belt 962 is carried over pulley 958 and a pulley 963 which is journaled on a support 964. A belt 967 is carried over pulley 963 and a pulley 968 which is journaled on a support 969. A belt 972 is carried over pulley 968 and a pulley 973 which is journaled on a support 974. A belt 977 is carried over pulley 973 and a pulley 978 which is journaled on a support 979. A belt 982 is carried over pulley 978 and a pulley 983 which is journaled on a support 984. A belt 987 is carried over pulley 983 and a pulley 988 which is journaled on a support 989. A belt 992 is carried over pulley 988 and a pulley 993 which is journaled on a support 994. A belt 997 is carried over pulley 993 and a pulley 998 which is journaled on a support 999. A belt 1002 is carried over pulley 998 and a pulley 1003 which is journaled on a support 1004.

same time the bristles take up the material by contact therewith and with the fabric 19 and also cause a current of air which sweeps the dust downwardly into the path of the printed sheet or other work on the conveyor. 5 The dusting material is thus kept in a finely subdivided form and so distributed and dispersed uniformly over the entire surface of the work and in quantities which may be 10 regulated to suit various conditions by selection of the fabric 19, by varying the speed of the brush 21 or its distance from and degree of engagement with the container wall portion 19, and the like as will occur to those skilled in the art. 15

The invention thus provides a dusting device by which the material is fed and carried directly against the work. If desired a hood 24 may be provided and connected with an 20 exhauster for carrying off and salvaging the dusting material not taken up by the work. The device is simple in construction and adapted to operate reliably with a minimum of attention and its construction and mode of 25 operation are such as to afford efficient application of the dusting material with a minimum of wastage and dissipation of the same in the surrounding atmosphere.

I claim as my invention:

50 1. In apparatus of the character described, the combination with work supporting means, of a container for a dusting material having a foraminous dispensing portion, and a brushing device rotatable in engagement with said dispensing portion and in unobstructed relation to said supporting means, to obtain material from said container and disperse the same over the work on said supporting means.

55 2. In apparatus of the character described, the combination with work supporting means, of a container for a dusting material having a foraminous wall portion through which said material may be sifted and a brush rotatable in external engagement with said wall portion to obtain said material therefrom and disposed in unobstructed relation to said supporting means to disperse said material over the work carried thereby.

60 3. In apparatus of the character described, the combination of work supporting means, of a container for a dusting material having a flexible, foraminous wall portion through which said material may be sifted, and a brush rotatable in engagement with said wall portion to agitate and sift said material therethrough, said brush being disposed in unobstructed relation to said supporting means to disperse material obtained from said wall portion over the work carried on said supporting means.

65 4. In apparatus of the character described, the combination with work conveying means, of a container for a dusting material having a flexible, foraminous wall portion through

which said material may be sifted, and a brush having spaced bristle portions and rotatable in engagement with said wall portion to agitate and sift said material therethrough, said brush being disposed in unobstructed relation to said conveying means for dispersing material obtained from said wall portion over the work carried by said conveying means. 70

5. In apparatus of the character described, the combination with work conveying means, of a container for a dusting material comprising a flexible, foraminous wall portion having a feeding inclination inwardly and downwardly to the bottom of the container and a brushing device rotatable in external engagement with said wall portion adjacent its bottom to agitate and sift said material therethrough, said device being arranged above said conveying means to receive the sifted material and to disperse the same by its rotation directly over the work carried by said conveying means. 75 80 85
